UNITED STATES PATENT OFFICE.

GEORGE R. PERRY, OF BROOKLYN, NEW YORK.

PUZZLE GAME.

Application filed April 8, 1922. Serial No. 550,563.

To all whom it may concern:

Be it known that I, GEORGE R. PERRY, a citizen of the United States, and a resident of Brooklyn, county of Kings, State 5 of New York, have invented certain new and useful Improvements in Puzzle Games, of which the following is a full, clear, and exact description.

Among the principal objects which the 10 present invention has in view are: To interest a player; to promote skill and judgment in handling the game; to provide amusement; and to simplify and cheapen the construction.

15 Drawings:

Figure 1 is a perspective view of a game apparatus, constructed and arranged in accordance with the present invention; and

20 Figure 2 is a section, taken as on the line 2-2 in Figure 1.

Description:

As shown in the drawings, a box-like structure or container is provided having a glass cover 7, which is supported by relatively heavy wooden strips 8. Each strip 25 8 is shown provided with a series of pins 9, the heads of which are covered by a strip of any suitable sealing means such as paper 10. The sealing strip is extended over the relatively thin bottom member 11, as well as 30 the glass cover 7. The bottom 11 and the sides 12 are preferably formed from cardboard, the structural strength being provided for the apparatus by the end pieces 35 8 and the glass cover 7.

In playing the game or solving the puzzle a series of rolling members or balls 13 are employed. These balls are pierced to provide small threading holes 14. The number 40 of balls has preferably a definite relation to the number of the pins in either series.

The game or puzzle consists in so manipulating the container as to place the balls on 45 the pins and in equal number throughout. That is to say, if there are ten balls, as shown in the drawings, the game and puzzle is to thread two balls on each of the pins 9 in either series. This is accomplished by 50 tilting the box so that the balls 13 are rolled to rest against one of the longer sides of the box. The distance from the side of the box adjacent to the end pin is about equal to half the diameter of the ball, which 55 means that if any ball is addressed properly to the point of the pin, the ball may be

caused to slide down over the pin. The length of the pins is such as to support two of the balls comfortably. The distance between the pins is such that when any pin is 60 filled with balls, no other ball can gain access between the balls on such pin and the adjacent pin. In the playing of the game it is recommended that the container be so held in either hand as to cause the balls to 65 roll to one side. One of the balls will then either lie adjacent to the point of the first pin or will become impaled thereon. The next ball in turn will come toward the same pin and will likewise lie either directly 70 against its point or will become impaled thereon as a result of light tapping on the edge of the container with the forefinger of the other hand. These may be brought into place readily by rolling along the adjacent side of the container. In all cases 75 care must be observed not to allow a ball to roll in front of the pin next to be covered, for the reason that if a ball enters the space between two adjacent pins there will 80 not be room enough for a ball to pass upon either of the pins and then permit said loose ball to pass out of such space without taking with it the impaled ball. In this connection it is to be noted that the arrangement of the pins and their relation to the bottom of the container are such that any impaled ball can not roll from its supporting pin, and any free ball in the container will roll and so change its position 85 90 more freely, or with less tilting of the container, than the impaled ball will slide from its pin. This fact facilitates the manipulation of the loose balls so as to bring them into favorable position for passing upon the 95 pins.

By a succession of light blows, the balls may be caused to vibrate or jump with slight rotation, which ultimately succeeds in disposing the hole 14 provided in each 100 ball opposite or in line with one of the pins, which may thereafter be threaded thereon. In this way the various pins become each provided with the proper number of balls 13.

When playing the game, two people may 105 be interested, in which case one player having threaded the balls on the pins upon his side of the box, hands the box to the other player, but in doing so lowers the edge thereof to dump or dislodge the balls from 110 the pins on which they have been by him threaded.

Claim:

An apparatus as set forth comprising a container having a transparent cover and also a rigid end piece, a series of pins carried by said end piece and projecting thence parallel to each other and spaced from and parallel to the bottom of the container, and a series of balls within the container each having a hole therethrough adapting it to

be received upon one of the pins, there being twice as many balls as there are pins in said series of pins, and the diameter of the balls being so proportioned to the spaces between adjacent pins that when any pin is filled with balls no other ball can gain access 15 between the balls on such pin and the next adjacent pin.

GEORGE R. PERRY.
